MACHINE FOR TREATING PIPES AND THE
LIKE

Horace L. Harrison, New York, N. Y.

Application December 19, 1928
Serial No. 326,929

22 Claims. (Cl. 242—11)

My invention is concerned with machines and/or apparatus for treating pipes, pipe lines, cables, or the like, and it is designed to produce a machine which can be used for cleaning the exterior of pipes, pipe lines or cables, or wrapping the same with felt or other flexible material, or for applying melted bitumen, or some similar coating material thereto, or for a combination of these treatments depending upon how and for what purpose the machine is equipped.

To this end it consists of a novel structure to which various implements may be applied and which will, when so equipped, carry said implements in a helical or circular path about the pipe or cable, as is necessary in wrapping the same, and which movement can be advantageously used in cleaning and coating such articles.

My invention is further concerned with such a structure mounted upon a self-propelled vehicle, the power plant of which may be employed to advance the vehicle, or operate the wrapping, ccating, or cleaning mechanism, or simultaneously for both purposes.

To these and various other ends, my invention consists in certain novel elements and combinations of elements, as will be hereinafter fully described, and the novel elements and combinations thereof particularly pointed out in the claims.

In the drawings:

Fig. 1 is a side elevation showing one form of my apparatus;

Fig. 2 is a plan view with the melting tank and oil reservoir removed;

Fig. 3 is a view similar to Fig. 1, but partly in central longitudinal section;

Fig. 4 is a front elevation on a larger scale;

Fig. 5 is a view in section on the line 5—5 of Fig. 1, but on a still larger scale;

Fig. 6 is a top plan view of the mechanism shown in Fig. 5, but with a portion of the framework removed, the view being substantially on the section line 6—6 of Fig. 5;

Fig. 7 is a central longitudinal vertical section of the mechanism seen in Figs. 5 and 6;

Fig. 8 is a view in section on the line 8—8 of Fig. 6;

Fig. 9 is a side elevation of a wheel which may be employed to convey the mechanism;

Fig. 10 is a view in section on the line 10—10 of Fig. 9;

Figs. 11 and 12 are fragmentary views illustrating modifications of the structure shown in Fig. 9;

Fig. 13 is a side elevation similar to Fig. 1 but showing a modification of the means for delivering the liquids through the apparatus;

Fig. 14 is a view in section on the line 14—14 of Fig. 13 but on a larger scale;

Fig. 15 is a central vertical section showing modified forms of cleaning mechanism;

Figs. 16, 17 and 18 are fragmentary views as seen in section on the lines 16—16, 17—17 and 18—18 of Fig. 15;

Fig. 19 is a central vertical section showing a modification of the felt applying mechanism;

Figs. 20 and 21 are views in section on the lines 20—20 and 21—21 of Fig. 19;

Figs. 22, 23 and 24 are top plan views and side elevations, respectively, of a modified mechanism for feeding the coating and covering mechanism along the pipe; and

Fig. 25 is a view similar to Fig. 1 but showing the mechanism employing an endless block chain tread instead of the wheels of Fig. 1.

Carrying out my invention in its preferred form, I employ a framework preferably constructed mainly of angle irons or other structural members and joined together in any desired manner so as to produce a strong frame to support and permit the movement of the various working elements and support a portion of pipe line already constructed in place. On the forward and top portion of the frame I mount a gasoline engine 30, where such engine is employed to furnish the power, and provide the same with the customary clutch and/or gear shifting mechanism 31 by which its shaft may be connected to the power shaft 32 journaled in

suitable bearings on the top of the frame. A tank 33 may be placed on the top of the frame and carry a supply of fuel oil for the burner 34, which heats the contents of the kettle 35 suitably mounted on the top of the frame and de-

signed to furnish liquid bituminous or similar coating material, the tank 33 being connected with the burner 34 by a pipe 36. The tank 33, or a portion thereof, may be employed to hold the gasoline, or other fuel, for the engine 30 and will be connected therewith by pipe 37 similar

to that shown. The framework is preferably mounted on four wheels, the rear wheels 38 being adapted to be driven by the gearing hereinafter described, while the front wheels 39 are mounted

in the manner similar to the front wheels of automobiles, made to follow paths parallel to axis of the pipe line and parallel to each other, being guided by the arms A which are attached

to steering knuckles B (Fig. 4) and also to suit-

60

70

75

80

85

90

95

100

105

110

able circular tie plate which bears on outside surface of the pipe.

As best seen in Fig. 4, I form in the front and rear of the framework, the support 45 of a generally inverted U-shape, and in said support I mount the top rollers 46 which are of the size and shape adapted to cooperate with the pipe 47 being operated on. Beneath the pipe I mount the similar rollers 48, the bearings 49 of which 10 are vertically movable in and removable from the frame 45, they being held pressed upward when in place by the helically coiled expanding springs 50 mounted in the frame. All of the mechanism subsequently described as located directly beneath the pipe 47 is arranged so that it 15 can be opened up, or a portion thereof removed, so that the pipe 47 can be lifted up from the trench 51, shown in Fig. 4, or from the surface of the ground, so as to bring the pipe 47 into 20 the position shown in Fig. 4. For the purpose of lifting the pipe by power, I show a journal in the central portion of the framework, toward the upper end thereof, the shaft 52, which has the drums 53 and 54 secured on the ends or 25 loosely mounted thereon, the drums 53 and 54 being loosely mounted on the shaft as shown adjacent to drum 53, and adapted to be connected therewith by the sliding clutch member 54a, which can be shifted into and out of operative position from the seat 44 by the connecting link 55 and the clutch shifting lever 56 pivoted on the frame at 57, as seen in Fig. 2. The shaft 52 has secured on its outer end the sprocket wheel 58, which is connected by the sprocket 30 chain 59 with the sprocket wheel 60 on the shaft 32 and adapted to be connected with the engine shaft by the clutch 31. When the pipe 47 is to be lifted into place, the customary tongs are placed about it and connected to cables or ropes 35 which will be wound on the drums 53 and 54 to lift the pipe as the shaft 52 is rotated.

Splined on the shaft 52 is the driving sleeve 61, best seen in Fig. 7, which has secured on the ends thereof the disks 62, which have the annular channels 63 in their peripheries adapted to cooperate with the peripheries of the pair of circular plates 64. The disks 62 are also provided with the sprocket teeth 65, so that they are, in effect, sprocket wheels. The circular plates 64 have the central opening to accommodate the pipe 47, and made up of two semi-circular sections, as seen in Fig. 8, the two sections being held in place by being secured by the bolts 66 to the castings 67, which are likewise made in semi-circular sections which are secured together by the bolts 68 and semi-circular plates 69, seen in Fig. 5. These bolts 68 and semi-circular plates 69 also serve to secure to the casting 67 the segments 70 having the helical flanges 60 on the peripheries thereof for a purpose to be hereafter described. The castings 67, when secured together, form as a part thereof a sprocket wheel on account of the sprocket teeth 72 formed thereon, as seen in Fig. 7. It also forms the major part of the annular receptacle 73, the inner face of which receptacle is formed by the annular brush coating or wiping member 74, which is provided with the inwardly projecting bristles 75 and with the apertures 76 there-through. These castings 67 are rotated by the sprocket chains 77 cooperating with the sprocket wheel 65 and the additional set of sprocket teeth 78 formed on the castings 67. The annular channels 73 may be supplied with suitable solvents 75 where the brushes or other scrubbing or wiping

members are used for cleansing, or with melted bitumen, etc., where they are used for coating the pipe 47. The solvents or melted bitumen, as the case may be, is taken from the kettle, or some similar container, by the flexible pipes 79, 80 seen in Fig. 1, secured at their upper ends to the T's 80, which are connected by the shut-off cocks 81 with the bottom of the kettle. The inner ends of the pipes 79 are connected through an aperture in the stationary annulus 82 Fig. 7, or as shown as 174 Fig. 19, held against the open side of the rotating annular chamber 73. With this construction, as the castings 67 are rotated, as hereinafter described, the liquid, whether water or solvent or paint material or melted bitumen, etc. can flow through the perforations 76 and to the brushes or wiping slings 75 which it is spread on the surface of the pipe 47. Where the pipe is to be wrapped with wire for any purpose, the spool 83 containing the wire 84 may be journaled upon a pin 85 held or mounted on one of the plates 64.

The two plates 64 are connected by the pair of rods 86 set diagonally and having the rollers 87 thereon, on which rollers are placed the rolls 100 of felt 88, seen in Fig. 1, which are applied to the pipe as they are rotated about the pipe and at the same time advanced along the length thereof. The angles at which the rods 86 are set relative to the line of the pipe will determine the pitch 105 of the felt wrapped thereon.

The rotary mechanism thus far described is supported by the pair of shafts 89 and 90, similar to the shaft 52, but journaled in the lower part of the frame and toward the sides thereof so 110 that the flanged disks 92 formed or secured on the ends of the driving sleeves 93 will support the adjacent edges of the circular plates 64. The castings 65 have been previously described as driven by the sprocket chains 77 and the sprocket 115 teeth 72 operate the sprocket chains 94 and 95, which cooperate with the sprocket wheels 96 and 97 (see Fig. 5), splined on the shafts 89 and 90, said sprocket wheels being rigidly secured to, or integral with, the respective ends of the driving sleeves 93. By the train of gearing thus described, when the shaft 52 is rotated through the connections heretofore described, the shafts 89 and 90 will also be rotated and the cleaning and wrapping units heretofore described will also 125 be rotated about the pipe.

As seen in Figs. 2 and 4, the shafts 89 and 90 each have secured thereon a sprocket pinion 98 connected by a sprocket chain 99, with a sprocket wheel 100, formed integrally with, or rigidly secured to, a clutch member sliding on a horizontal shaft 101, which has secured thereon a cooperating clutch member 102. Customary means for engaging and dis-engaging the sliding clutch member 100 will be employed. The other end of 130 the shaft 101 is provided with a worm 103 indicated in dotted lines in Fig. 1 and meshing with a worm gear wheel 104 secured on the hub of the wheels 38. The gearing thus described may be timed or arranged by suitable alternate construction so as to advance the entire machine over the ground at the same or related speed to that speed by which the pipe is treated and wound by the mechanism rotating about it for that purpose, heretofore described.

Under some conditions, however, it is desirable to operate the apparatus while the machine is standing still, and where this condition exists, the mechanism to be now described must be employed:

145

150

As best seen in Figs. 5 and 6, the helical flanges or teeth 71 on the peripheries of the wheels 70 mesh or engage the idle friction rollers 105, which are journaled on the ends of the rivets or pins 106 which connect the links 107 and 108 of the endless chains seen in Figs. 1 and 3. The lower run of these chains are guided between the angle irons 109 and 110, seen in Figs. 1, 3 and 5, while the upper run may be guided by angle iron 111, seen in Fig. 1. The chains are sprocket chains carried by the pair of sprocket wheels 112 journaled in the forward end of the frame, and 113 journaled in the rear end of the frame. Assuming that the chains are held stationary as by locking the wheel 112 or 113 and, as the wheels 70 rotate, their helical flanges 71 will cause them to be advanced slowly from the position shown in the rear of the machine in Fig. 1, to a corresponding position in the forward end of the machine. If the machine is stationary and the wheels 70 are to be returned from the position in the forward end of the machine to that in the rear end of the machine, then the wheels 112 must be rotated in a clockwise manner, and the lower run of the chain engaging the helical flanges 71 will carry the wheels 70 and the entire cleaning and wrapping mechanism to the rear. To rotate the wheels 112, I employ the mechanism shown in Figs. 1 and 2, where it will be seen that the shaft 32 has on the rear end thereof the bevel friction gear 114 adapted to mesh or engage the bevel pinions 115 splined on the transverse shaft 116, journaled in suitable bearings on the framework. The position of the pinions 115 is controlled by the handle 117 located at the seat 44 and connected to the bell crank lever 118 fulcrumed on the frame and in turn connected by the link 119 to the bell crank lever 120 likewise fulcrumed on the frame and connected by the link 121 to the bell crank lever 122 fulcrumed on the forward portion of the frame and having at its inner end the customary fork for engaging the annular channel in the clutch shifting mechanism for the bevel pinions 115. The ends of the shaft 116 have secured thereon the belt wheels 123 which are connected by the belts 124 with the belt wheels 125 secured on the outer end of the shafts 126, which have the sprocket wheels 112 secured on the inner ends thereof. By the connections shown, it will be obvious that the cleaning and wrapping mechanism may be shifted by power from the front to the rear of the machine while the whole is at rest or continuously operated.

I have previously described the annular receptacles 73 and the brushes 75 as used either for cleaning the pipe when solvents or abrasives are supplied thereto, or for coating the pipe when the melted bitumen, paint material, etc., is employed. Under some circumstances, I may want to smooth the fabric that is applied from the rolls 88 and coat the same, and for this purpose I may employ what I call the ironing shoes, shown in Figs. 6 and 8, where it will be seen that the rods 127 connect the plates 64 and have secured thereon the bearings 128 in which slide the circular hollow stems 129 of the hollow shoes 130. An expanding spring 131 in the hollow stems serves to hold the shoes yieldingly against the pipe 47. The hollow shoes are supplied with the bitumen from the annular channel 73 by the flexible tubes 132 let into the channel 73 at one end while the other ends, as seen in dotted lines in Fig. 8, enter the rear wall of the shoes. These shoes are provided with the perforations 133 by which the

bitumen can pass from the shoes on to the fabric wall and wound on the pipe 47, but which is not shown in Fig. 8.

Referring to Fig. 5, it will be seen that the ring 82, constituting the stationary side of the annular chamber 73 is split horizontally, so that the lower half can be removed in bringing the pipe 47 into place, and that the two halves are connected by bolts 134 passed through the ends of the brace bars 135 and into the body of the ring. These brace bars extend upwardly and outwardly, their upper ends being made parallel to the sides of the frame and being preferably provided with the anti-friction rollers 136 designed to cooperate with the underside of the angle bars 137 constituting a part of the horizontal top of the frame. I may rivet to the upper ends of these bars 135, the cross bars 138 which may have a curvature in the center thereof to accommodate the sleeve 61.

In Figs. 9 and 10, I show a preferred form of construction for the wheels 38 and 39, where it will be seen that the central spider 140 carrying the hub has the rim 141 which carries the yokes 142 which embrace one side of the springs 143, the ends of which are fulcrumed to the links 144, the other ends of these links are fulcrumed to the bearings 145 secured on the inner periphery of the heavy combined rim 146 which may be of any desired design for traction purposes. In Fig. 11, I illustrate a modification in which instead of employing the complete elliptical springs 143, I employ the semi-elliptical springs 147, and in Fig. 11, I show the ends connected by the links 148 pivotally connected to the links 144, so that the flexure of the springs may be limited. In Fig. 12, I show a similar construction, except that instead of employing the rigid link 148, I employ a helically coiled contractile spring 149 which functions somewhat as the omitted side of the elliptical spring as well as a link.

In Figs. 13 and 14, I illustrate a modification in which the melted bitumen, or wash solution, as the case may be, is delivered to the annular receptacles 73 by rigid connections instead of the flexible tubes 79, shown in Fig. 1. In this modification, the melted bitumen or cleansing solvents, or whatever liquid is employed, is delivered from the kettle 35 through a pair of pipes 150 leading downwardly and outwardly therefrom and discharging into the parallel troughs 151 which are supported by connections 152 to the brace bars 135, as well as by the tubes 153 leading therefrom to the respective annular chambers 73 which they supply with the melted bitumen in all positions of the cleaning and wrapping mechanism, since the troughs 151, as best seen in Fig. 13, are of sufficient length so that they will be beneath the pipes 150 in all possible positions of said wrapping mechanism. These troughs may be designed as either open or closed to the atmosphere.

In Figs. 15 to 18, I illustrate modifications of the construction of the cleaning and brushing mechanisms, as it will be seen that on the right-hand side in Fig. 1, I substitute for the brushes or bristles heretofore described, a set of annular abrading rings 154, which may be composed of any desirable material for that purpose and which are pressed into service by the helically coiled expanding springs 155 interposed between the inner periphery of the channeled ring 156 forming the inner periphery of the hollow chamber 73 and the curved plates 157 which bear directly on the abrading rings. At the center of said Fig. 15, I illustrate an annular cleaning brush or sand blast applying annular nozzle rings, 150

which is supported by a plurality of cross bars 159 secured to its outer periphery and in turn secured by their upturned ends to the adjacent walls of the plates 64. The inner periphery of the ring 158 is provided with the customary bristles and/or nozzles and it also has the numerous perforations 160 through which water, sand or solvents can enter the ring as it rotates from the transverse pipe 161 having the perforations in its underside and having the pipe 162 connected thereto by the tee 163, said pipe 162 being connected to the kettle 35 or any other suitable supply of cleaning or abrading material. I also illustrate the stationary pipe ring 164, which encircles the transverse bars 159 and is supported from the vertical pipe 165, which may be connected to the kettle or other suitable supply of air, sand or solvents, or whatever cleansing medium is employed which is discharged through the perforations 166 on the inner periphery of the pipe ring. It will be understood that in carrying out my invention I may employ any desirable combination of these various cleansing devices.

In Figs. 19 to 21, I illustrate another modification of the pipe wrapping mechanism, in which the supporting rods 167 for the rolls of felt 88 instead of being rigidly connected to the adjacent faces of the plates 64, are connected by the universal joints 168 at their ends with the supports 169 which may be adjusted in the slots 170 (see Fig. 20), formed in the face of the modified plates 64, shown in said Figs. 19 and 20. These supports 169 can be secured in any desired position of adjustment in the slots 170 by nuts securing on the threaded ends thereof and cooperating with the inner face of the flanged portion of the plates 64. By this means it will be obvious that the angle at which the rods 167 extend relative to the pipe 47 may be adjusted as desired so as to change the angle at which the felt is applied, and thus the pitch, as it were, of the winding. In this modified form shown in Figs. 19 to 21, the melted bitumen may be delivered from the troughs 151 through the pipes 171 to the T 172, by which they are connected to the short pipe 173 which delivers the liquid to the stationary annular reservoir 174, which, as seen in Fig. 19, is open on one side so as to communicate with the annular reservoir 175, similar to the previously described reservoir or chamber 73, but much larger, its other end being closed by the annular plate 176. The two reservoirs 175 illustrated are connected by a plurality of pipes 177 with the liquid spreaders 178, valves 179 being placed in the pipes 177 so that the flow of the liquid therethrough can be controlled. The shoe of the spreader 178 is connected with the portion 180 which first receives the liquid by the pipe 181, and this shoe or spreader 178 is of similar internal construction as the shoe or spreader 130, shown in Fig. 8.

Thus it will be seen that with the adaptation of the rods and universal joints 168, Fig. 19, that the coating, cleaning and/or wrapping mechanism can also be designed to be flexible so as to follow and clean, coat or wrap a curved pipe line.

In Figs. 22 and 23, I have illustrated a modified structure for feeding the fluid applying and wrapping mechanism longitudinally of the pipe 70 to take the place of the helical flanges 71 cooperating with the rollers 105. In this form of mechanism, I employ a ring 182 connected to the liquid applying and wrapping mechanism and made in two parts so that it can be placed about the pipe 47, and on this ring I place a pair of

arms 183, which are preferably angularly adjustable by means of the slot 184 therein with which the bolt 185 cooperates. In the ends of these arms 183, I place a threaded aperture through which the threaded end 186 of the fork 187 is threaded and secured by the lock nut 188. The fork 187 has journaled therein a pair of rollers 189 which engage the surface of the pipe 47, and are pressed against the same by the adjustment of the threaded stem 186 in the arm 183. It will be obvious that with the rollers 189 set at the angle shown, the tendency is, as the ring 182 is rotated about the pipe 47, to draw said ring 182 longitudinally of the pipe, its actual path being that of a helix. These rollers 189 may be attached as shown in any necessary numbers and/or set in a yoke so that paths of individual sets will run in tandem, as seen in Fig. 24. In Fig. 19, I show additional discs 195 which can be used to support further rolls of felt, paper, fabric, etc., in a manner similar to that above described.

Thus it will also be obvious that by application of power to shaft 193 (Fig. 4) on the front end of the apparatus and similarly on the rear end 100 of the machine, separate or joined lengths of pipe may be automatically fed in the front end and discharged from the rear when it may be desired to utilize my invention in this manner for operating in a plant, mill, yard or adjacent 105 to a pipe line to be constructed. Separate lengths of pipe may thus be cleaned, painted, coated and/or wrapped.

If it is also desired that each of the operations as set forth above may be carried on separately 110 or in conjunction with each other, the machines and/or apparatus may be operated as units, in tandem. Thus, one unit cleaning followed by other units painting and/or coating and wrapping—accomplishing any desired form of organized operation simultaneously without necessitating a separate set-up of each apparatus.

In Fig. 25 I show a modification of my invention which is similar in all respects, with the exception that the large sprocket wheels 190 and 120 191 take the place of the wheels 38 and 39 of the form shown in Fig. 1, and the wheels 190—190 have the power applied thereto. These large sprocket wheels have mounted thereon the endless block chain treads 192—192 which furnish 125 the desired tractive power that can be applied for soft ground in which the wheels 38 and 39 would be mired.

While I have shown and described my invention as embodied in various forms which I at 130 present consider well adapted to carry out its purposes, it will be understood that it is capable of numerous additional modifications and that I do not desire to be limited in the interpretation of the following claims except as may be necessitated by the state of the prior art.

What I claim as new, and desire to secure by Letters Patent of the United States is:

1. In a device of the class described, the combination with a relatively stationary frame, of 140 pipe treating mechanism adapted to be moved in a helical path about a pipe held in the frame, means for moving said pipe treating mechanism in said helical path consisting of mechanism for rotating said pipe treating mechanism, and a 145 helical flange carried thereby cooperating with projections on a pair of endless chains carried by said frame, which chains can be advanced or retracted.

2. In a device of the class described, the com- 150

- bination with a relatively stationary frame, of pipe treating mechanism adapted to be moved in a helical path about a pipe held in the frame, means for moving said pipe treating mechanism 5 in said helical path consisting of mechanism for rotating said pipe treating mechanism, and a helical flange carried thereby cooperating with anti-friction rollers on an endless chain carried by said frame, which chain can be advanced or retracted thereon.
- 10 3. In a device of the class described, the combination with a relatively stationary frame, of pipe treating mechanism adapted to be moved in a helical path about a pipe held in said frame, and means for moving said pipe treating mechanism in said helical path including three rotatable shafts in said frame, chain and sprocket gearing connecting the three shafts to rotate them in unison, the sprocket wheels on the three shafts 15 being connected to a sleeve on each shaft, which sleeve carries guide disks for the pipe treating mechanism rotating therein.
- 20 4. In a device of the class described, a pipe treating element consisting of an annular container adapted to have a rotative movement relative to a pipe which it encircles and having perforations through its inner periphery, and abrasive means projecting inwardly therefrom to contact with the pipe.
- 25 30 5. In a device of the class described, a pipe treating element consisting of an annular container open at one side adapted to have a rotative movement relative to a pipe which it encircles and having perforations through its inner periphery, and abrasive means projecting inwardly therefrom to contact with the pipe, means for rotating said element, and a stationary ring closing its open side and having a pipe opening thereinto.
- 35 40 6. In a device of the class described, a pipe treating element consisting of a hollow shoe having its inner periphery adapted to fit on the surface of a pipe, the pipe and element being relatively rotatable, perforations in said inner periphery, means for supplying liquid to the interior of the shoe, and a spring to press the shoe toward the pipe.
- 45 50 7. In a device of the class described, a pair of pipe treating elements each consisting of an annular plate encircling the pipe, a sprocket wheel concentric therewith and connected thereto, and a liquid containing annular chamber likewise concentric therewith and having perforations on its inner periphery, of a plurality of spindles connecting said annular plates and set at an angle thereto and carrying rolls of wrapping material to be wrapped around the pipe.
- 55 60 8. In a device of the class described, the combination with a relatively stationary frame, of a liquid holder fixed therein having a spout depending therefrom, pipe treating mechanism including an element for applying liquid to said pipe, means for moving said pipe treating mechanism longitudinally of said pipe, an elongated trough connected to and moving with said pipe treating mechanism into which trough the spout discharges, and connections through the trough to the liquid applying element.
- 65 70 9. In a device of the class described, the combination with an annular brush encircling the pipe with its bristles engaging it and having perforations through the back thereof, of means for rotating and advancing the brush, and a header pipe above the brush and advancing with it and
- having perforations to discharge a liquid upon the external periphery of the brush.
10. In a device of the class described, the combination with a relatively stationary frame, of pipe treating mechanism mounted therein and movable in a helical path relative to the pipe to be treated, a fabric roll holder carried by said pipe treating mechanism arranged to wrap fabric around the said pipe, and means for adjusting the angle at which said roll holder extends relative to the pipe, said means consisting of two supports adjustable relative to each other and universal joints between the adjacent ends of the supports and the adjacent ends of the roll holder. 80
- 15 11. In a device of the class described, the combination with a relatively stationary frame, of pipe treating mechanism carried thereby and adapted to encircle the pipe carried by the frame and to be moved in a helical path relative thereto, and means for causing said pipe treating mechanism to advance along the pipe as it is rotated, said means consisting of rollers carried by the pipe treating mechanism and engaging the periphery of the pipe and set with the axes of the rollers at an acute angle to the axis of the pipe. 90
- 20 25 12. In a device of the class described, the combination with a relatively stationary frame, of a pipe treating mechanism carried thereby and adapted to encircle the pipe carried by the frame and to be moved in a helical path relative thereto, and means for causing said pipe treating mechanism to advance along the pipe as it is rotated, said means consisting of two sets of diametrically opposed rollers carried by the pipe treating mechanism and engaging the periphery of the pipe and set with the axes of the rollers at an acute angle to the axis of the pipe. 100
- 30 35 13. In a device of the class described, the combination with a relatively stationary frame, of pipe treating mechanism carried thereby and adapted to encircle the pipe carried by the frame and to be moved in a helical path relative thereto, means for causing said pipe treating mechanism to advance along the pipe as it is rotated, said means consisting of rollers carried by the pipe treating mechanism and engaging the periphery of the pipe and set with the axes of the rollers at an acute angle to the axis of the pipe, and means for adjusting their angle and position relative to the pipe. 110
- 40 45 14. In a device of the class described, the combination with a chassis adapted to straddle the article to be treated, of a rotatable treating member adapted to receive the article and means for longitudinally moving the same in the chassis, 115 said member being separable to get the articles in place, and means for advancing the chassis and the said treating member carried thereby, along the article treated; the said means for moving the said treating members longitudinally of the 120 chassis including extruded spiral treads formed on the rotating treating members, cooperating with relatively stationary abutments. 125
- 50 55 15. In a device of the class described, the combination with a chassis adapted to straddle the article to be treated, of a rotatable treating member adapted to receive the article and means for longitudinally moving the same in the chassis, said member being separable to get the article in place, and means for causing a longitudinal movement 130 of the treating member when it is not rotating; the said means for moving the said treating members longitudinally of the chassis including extruded spiral treads formed on the rotating treat- 135

ing members, cooperating with relatively stationary abutments.

16. In a device of the class described, the combination with a chassis adapted to straddle the article to be treated, of a rotatable treating member adapted to receive the article and means for longitudinally moving the same in the chassis, said member being separable to get the article in place, and means for causing a longitudinal movement of the treating member when it is not rotating, said means adapted to cooperate with the treating member to cause its longitudinal movement when it is rotated; the said means for moving the said treating members longitudinally of the chassis including extruded spiral treads formed on the rotating treating members, cooperating with relatively stationary abutments.
17. In a device of the class described, a pipe treating element consisting of an annular container adapted to have a rotative movement relative to a pipe which it encircles and having perforations through its inner periphery and means for ejecting sand on the pipe through the said perforations.
18. In a device of the class described, the combination of a relatively stationary frame of pipe-treatment mechanisms, including annular containers, mounted for rotation relative to the pipe to be treated, said containers having nozzle openings in the inner periphery thereof for introducing cleaning means to the surface of the pipe being treated.
19. In a device of the class described, a pipe treating element consisting of an annular con-

tainer opened at one side, adapted to have a rotative movement relative to a pipe which it encircles and having perforations through its inner periphery, nozzles and bristles on the inner circumference of the said annular container and means for applying solvents through the said nozzles while the bristles act on the surface of the pipe being treated.

20. In a device of the class described, a pipe treating element comprising an annular container adapted to have a rotative movement relative to a pipe which it encircles, and having perforations through its inner periphery, and means by which abrasive material is contacted with the pipe.

21. In a device of the class described, a pipe treating element comprising a hollow shoe having its inner periphery adapted to fit on the surface of a pipe, the pipe and element being relatively rotatable, perforations formed in its inner periphery, means for supplying liquid to the interior of the shoe, and means for actuating the shoe toward the pipe.

22. In a device of the class described, the combination with a relatively stationary frame, of pipe treating mechanism carried thereby encircling a pipe carried by the frame and movable in a helical path relative thereto, means for moving said pipe treating mechanism in said helical path, endless means for supporting and transporting the device on soft ground, said means including block chain treads for said frame, and gearing for moving the treads.

HORACE L. HARRISON.
